UNITED STATES PATENT OFFICE.

WILLIAM H. H. GRIFFIN, OF GOREE, TEXAS.

RING FOR DISSEMINATING PERFUMES, &c.

1,257,848.

Specification of Letters Patent. Patented Feb. 26, 1918.

Application filed May 11, 1917. Serial No. 168,057.

To all whom it may concern:

Be it known that I, WILLIAM H. H. GRIFFIN, a citizen of the United States, residing at Goree, in the county of Knox and State 5 of Texas, have invented new and useful Improvements in Rings for Disseminating Perfumes, &c., of which the following is a specification.

This invention relates to an improved 10 device for disseminating chemicals, perfumes and the like, said device being in the nature of a ring which may be worn on either finger, toe, arm or any part of the body and which constitutes a container for 15 the material to be disseminated.

A further object of the invention is to produce a ring of the character described 20 constituting a container and having an outlet opening or openings which are normally obstructed to some extent by contact with 25 the member on which it is worn so that the escape of the material contained will be slow and gradual.

With these and other ends in view which 30 will readily appear as the nature of the invention is better understood, the same consists in the improved construction and novel arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, but that changes, alterations and modifications within the scope of the claims may be resorted to when desired.

In the drawings:—

40 Figure 1 is a perspective view of a ring constructed in accordance with the invention.

Fig. 2 is a transverse sectional view.

45 Fig. 3 is a sectional view taken on the line 3—8 in Fig. 2.

Fig. 4 is a view similar to Fig. 3, but illustrating a slight modification.

Fig. 5 is a perspective view illustrating a further modification.

50 Fig. 6 is a sectional view taken on the line 6—6 in Fig. 5.

Fig. 7 is a perspective view illustrating a still further modification.

Corresponding parts in the several figures 55 are denoted by like characters of reference.

The ring 15, as seen in Figs. 1, 2 and 3,

may be of tubular material of any kind so as to form within said ring a circumferential recess 16 communicating with a hopper-shaped inlet 17 having a detachable 60 tightly fitting cap, cover, screw or stopper 18 which may be ornamented in any desired way by a gem setting or the like. The inner wall of the tubular ring is provided with a small opening or openings 19 which are directed toward the center of the ring so that when the latter is placed on the body or any member thereof said opening or openings will be partly obstructed by contact with such member. The circumferential 70 space 16, as well as the inlet hopper 17, may be filled with any desired chemical or perfume which will be permitted to escape slowly and gradually, being thus applied directly to the person of the wearer. In this 75 manner perfumes and various potent healing chemicals may be advantageously disseminated and applied without inconvenience.

Under the slightly modified construction 80 illustrated in Fig. 4 the ring, here designated by 20, is made of solid material, but is provided with a recess 21 extending partly around the circumference thereof and having a discharge opening or openings 22 and 85 an inlet 23 provided with a detachable cap, cover, screw or stopper 24.

In Figs. 1 to 4, inclusive, the tubular portion of the ring has been shown as being of circular cross section. In Figs. 5, 6 and 7 90 the ring has been shown as being composed of a flattened tube 30, it being desired to be understood that no limitation whatever is made to the particular shape of the tubular receptacle. In Figs. 5, 6 and 7 the hopper-shaped inlet is omitted, and a simple inlet aperture 31 is provided in the exterior wall of the tube, said inlet being closed in Figs. 5 and 6 by a screw plug 32, and in Fig. 7 by means of solder, as indicated at 33. The 100 inner wall of the tube is in each instance provided with one or more escape apertures, as indicated at 34.

From the foregoing description taken in connection with the drawing, it will be seen 105 that I have produced a simple and efficient device for disseminating perfumes and chemicals which may be worn as an article of personal adornment, it being obvious that its use is not limited to that of a finger ring, 110 but it may be sufficiently large to serve as a bracelet and for other purposes.

It will be particularly understood that no limitation is made with respect to the specific construction of the ring formed receptacle. Likewise, no limitation is made with respect to the construction of the inlet, the means for obstructing the same or to the number or disposition of the outlet apertures. It is to be understood, however, that the inner face of the ring, and especially where the outlet apertures are formed, must be preferably smooth and polished, it being important in the formation of the outlet apertures to avoid the formation of any fins or projections that would tend to abrade or to irritate the skin of the wearer.

Having thus described the invention, what is claimed as new, is:—

1. A finger ring for disseminating perfumes and the like, the same having a cavity, a smooth inner face to contact with

the wearer, an inlet and a discharge opening connecting the cavity with the smooth inner face, said opening to be obstructed by contact with the wearer.

2. A finger ring for disseminating perfumes and the like, the same having a cavity, a smooth inner face to contact with the wearer, a discharge opening connecting the cavity with the smooth inner face, said opening to be obstructed by contact with the wearer, a hopper shaped inlet communicating with the cavity and a tightly fitting detachable ornamental closure for said inlet.

In testimony whereof I affix my signature in presence of two witnesses.

WILLIAM H. H. GRIFFIN.
